DESIGN FOR A MOTOR DRIVEN CRAFT

Fred Muschler, Denville Township, Morris County, N. J.

Application August 8, 1933. Serial No. 48,967

Term of patent 7 years

To all whom it may concern:

Be it known that I, FRED MUSCHLER, a citizen of Germany who has declared his intention of becoming a citizen of the United States, residing in the township of Denville, in the county of Morris and State of New Jersey, have invented a new, original, and ornamental Design for Motor Driven Craft, of which the following is a specification, reference being had to the accompanying drawing, forming a part hereof.

In the drawing,

Fig. 1 represents a side elevational view of a motor driven craft, embodying my new design, Fig. 2 is a bottom plan view thereof, and Fig. 3 is an end elevational view thereof.

I claim:

The ornamental design for a motor driven craft, as shown.

FRED MUSCHLER.
